UNITED STATES PATENT OFFICE.

JOHN ARBUCKLE, OF BROOKLYN, NEW YORK, ASSIGNOR TO THE WOMAN'S SUNSHINE PUBLISHING COMPANY, OF NEW YORK.

DESIGN FOR AN ORNAMENTAL PATTERN OR PRINT FOR BOOK-COVERS, &c.

SPECIFICATION forming part of Design No. 26,452, dated December 29, 1896.

Application filed July 9, 1896. Serial No. 598,614. Term of patent 14 years.

To all whom it may concern:

Be it known that I, JOHN ARBUCKLE, a citizen of the United States, residing in Brooklyn, in the county of Kings and State of New York, have invented and produced a certain new and original Design for an Ornamental Print or Pattern for Books and the Like, of which the following is a specification.

This design relates to ornamental prints or patterns for the covers of books and magazines or publications and for the first pages or title-pages thereof, and provides an original print or pattern for ornamenting such objects,

The new design is shown in the accompanying drawing.

The distinctive features of the new design are an oval or elliptical central frame or border A, surmounted and flanked by fluttering ribbons or streamers B, in conjunction with a plurality of pictorial representations beneath and at the sides of said frame, and a distinctive pictorial representation in the space within the latter. These representations are serial or successive in character and are lettered C, D, E, F, and G, respectively. The picture C illustrates a children's game and is at the lower left-hand side of the frame A. The picture D represents a marriage ceremony and is at the lower right-hand side of

such frame. The picture E represents motherhood and occupies a central position within the frame, while the pictures F and G represent successive stages of domestic life and are disposed, respectively, at the left and right hand-sides of the pictures C and D. The frame A has a series of circular bulbous or bead-like ornamentations *a* on its face. The ribbons B are knotted in a ring *c*, from which the frame A hangs as a pendant, and the ribbons have bows or loops *d* at the sides of this ring. One end of one ribbon falls between the pictures F and C and one end of the other ribbon falls between the pictures D and G, while the other end of each ribbon flutters across its falling end above the two adjacent pictures.

What I claim is—

The design for an ornamental print or pattern for book-covers and magazines, substantially as shown and described.

In witness whereof I have hereunto signed my name in the presence of two subscribing witnesses.

JOHN ARBUCKLE.
